UNITED STATES PATENT OFFICE.

EDWIN L. RUSSELL, OF CLEVELAND, OHIO.

INTERNAL-COMBUSTION ENGINE.

1,099,102.

Specification of Letters Patent.

Patented June 2, 1914.

Application filed August 21, 1911. Serial No. 645,223.

To all whom it may concern:

Be it known that I, EDWIN L. RUSSELL, a citizen of the United States, residing at Cleveland, in the county of Cuyahoga and 5 State of Ohio, have invented a new and useful Internal-Combustion Engine, of which the following is a specification.

The object of my invention is to produce a rotary valve structure in association with 10 a chamber in which there are sudden increases of pressure, such for instance as the cylinder of an internal combustion engine, the construction of the valve and the valve driving mechanism being such that, while 15 the valve may yield from its seat under gradually applied force, it will be retained momentarily upon its seat against suddenly applied forces.

In the accompanying drawings, which 20 illustrate my invention, Figure 1 is an axial section through the valve casing, and Fig. 2 is a bottom view of part of the driving connection.

In the drawings, 10 indicates the cylinder of an internal combustion engine of an ordinary type in which there are sudden increases of pressure. Communicating with the cylinder 10, in any desired manner, is a valve chamber 11 in which is mounted a 25 valve 12, in the present drawings the valve being shown as a tapered plug valve. Valve 12 is so mounted within its casing that it may not only move along its seat (*i. e.* rotatively in the present instance), but may 30 also be moved toward and from its seat (*i. e.* axially in the present instance), and the said valve is provided with suitable passages by means of which desired coöperating 35 passages may be controlled. The 40 valve is normally held to its seat by its own weight, (and an added spring if desired) and is connected to a driving shaft 13 in such manner that under certain conditions, where there is an abnormal resistance of 45 the valve to movement along its seat, there may be relative movement between the driver and the valve such as to cause a movement of the valve bodily toward or from its seat. In the present form this driving 50 connection comprises a V-shaped slot 14 across the face of an annular head 14^a carried by shaft 13, and a coöperating and correspondingly V-shaped projection 15 extending across the face of an annular head 55 15^a carried by the valve, the arrangement being such that rotation of the shaft 13

in either direction, while the valve is stationary, will cause a movement of the valve away from its seat. The friction between the projection 15 and the sides of the slot 14 will, if the resistance of the valve 12 to movement along its seat be not too great, drive the said valve along its seat. Whenever there is a lifting of the valve from its seat its resistance to movement along its seat will be decreased.

In the arrangement shown, sudden increases of pressure within cylinder 10 may at time act upon valve 12 to tend to lift it from its seat and, in order to prevent this action, I provide the valve at its upper end with a dash-pot piston 16 fitted within a dash-pot 17. Communicating with the dash-pot 17 is a supply passage 18 leading from a reservoir 19 and supply passage 18 75 is controlled by a valve 21 which permits free flow from reservoir 19 to dash-pot 17 but prevents, or restricts, flow from dash-pot 17 to reservoir 19. A by-pass 22 leads from dash-pot 17 to reservoir 19. The application of driving force to valve 12 from driving shaft 13 through the connection 14-15 is gradual and the possible flow through pass 22 is sufficient to permit axial movement of the valve upon relative movement of the driver but if there be a suddenly applied force tending to lift valve 12 it will be resisted by the dash-pot construction, as will be clearly apparent.

I claim as my invention:

1. The combination, with a chamber subject to sudden increases of pressure, of a passage communicating with said chamber and having a valve seat, a valve mounted on said seat and movable away from said seat as well as along said seat, a driver for said valve, interengaging members carried by said valve and driver permitting independent advancement of the driver to cause movement of the valve away from its seat, and a dash-pot connected with the valve and resisting sudden movements of the valve away from its seat.

2. The combination, with a chamber subject to sudden increases of pressure, of a passage communicating with said chamber and having a valve seat, a valve mounted on said seat and movable away from said seat as well as along said seat, a driver for said valve, interengaging members carried by said valve and driver permitting independent advancement of the driver to cause movement of the valve away from its seat, and a

dash pot connected with the valve and resisting sudden movements of the valve in one direction.

3. The combination, with a chamber subject to sudden increases of pressure, of a passage communicating with said chamber and having a valve seat, a rotary axially tapered valve mounted in said chamber on said seat and axially movable, a driver for said valve, interengaging members carried by said valve and driver permitting independent angular advancement of the driver to cause axial movement of the valve away from its seat, and a dash pot connected with the valve and resisting sudden movements of the valve away from its seat.
4. The combination, with a chamber subject to sudden increases of pressure, of a passage communicating with said chamber and having a valve seat, a rotary axially tapered valve mounted in said chamber on said seat and axially movable, a driver for said valve, interengaging members carried by said valve and driver permitting independent angular advancement of the driver to cause axial movement of the valve away from its seat, and a dash pot connected with the valve and resisting sudden movements of the valve axially.
- 30 5. The combination, with a chamber sub-

ject to sudden increases of pressure, of a passage communicating with said chamber and having a valve seat, a valve mounted on said seat and movable away from said seat as well as along said seat, a driver for said valve, interengaging members carried by said valve and driver permitting independent advancement of the driver to cause movement of the valve away from its seat, and a plastic abutment for said valve.

3. The combination, with a chamber subject to sudden increases of pressure, of a passage communicating with said chamber and having a valve seat, a rotary axially tapered valve mounted in said chamber on said seat and axially movable, a driver for said valve, interengaging members carried by said valve and driver permitting independent angular advancement of the driver to cause axial movement of the valve away from its seat, and a plastic abutment for the valve axially thereof.

In witness whereof, I, have hereunto set my hand and seal at Indianapolis, Indiana, this 16th day of August, A. D. one thousand nine hundred and eleven.

EDWIN L. RUSSELL. [L. S.]
